UNITED STATES PATENT OFFICE.

MICHAEL E. HERBERT, JR., OF CHICAGO, ILLINOIS.

WATER-HEATER.

SPECIFICATION forming part of Letters Patent No. 634,345, dated October 3, 1899.

Application filed January 19, 1899. Serial No. 702,660. (No model.)

To all whom it may concern:

Be it known that I, MICHAEL E. HERBERT, Jr., of Chicago, in the county of Cook and State of Illinois, have invented a new and useful Improvement in Water-Heaters, of which the following is a specification.

My invention is a water-heater of that class which is used for heating water for bath and domestic purposes and other uses where a circulation of hot water is desired. It employs a water-jacketed feeding-magazine; and it chiefly consists in the construction of the boiler of two main parts, the upper part having the pendent annular water-chamber and the lower part inclosing or forming the fire-box, which two parts are connected for circulation by a series of vertical pipes, all as hereinafter more fully described.

Figure 1 is a perspective view of the heater with a part of the outer jacket broken away. Fig. 2 is an enlarged vertical central section taken through the smoke-pipe and front door. Fig. 3 is a partial horizontal section on line 3 of Fig. 2. Fig. 4 is a similar section on line 4 4; and Fig. 5 is a perspective view of the two main parts of the heater, which are made of cast-iron, each in a single piece.

The upper part of my heater consists of a short cylinder A, having a central and downwardly-projecting annular chamber A', forming a magazine for fuel open at top and bottom and formed of two walls that inclose an annular space in open communication with the upper part A of the boiler and forming an inclosing water-jacket for the magazine.

The lower part of the boiler B is of the usual construction, simply being a water-cased fire-box, with door B'. This portion B of the boiler, however, stops short at a point 40 a little above the lower end of the central magazine and is connected to the upper portion A of the boiler by a circular series of vertical water-tubes C, which are tapped or otherwise secured into the upper surface of 45 boiler-section B and the lower surface of boiler-section A, so as to establish a free and full communication between these two parts for the circulation of water. Around the outside of these tubes C there is an inclosing 50 jacket F, of sheet metal, which extends from the outer periphery of the boiler-section A to

the outer periphery of the boiler-section B, and thus completing the exterior of the heater.

Through the upper boiler-section A there are four (more or less) segmental openings a, 55 which give passage for the hot products of combustion from the fire-chamber below to the smoke-hood E above and thence out through the smoke-pipe e. This hood E rests detachably on the upper portion A of the 60 boiler and has an inlet-door D for fuel and a chute d, leading therefrom into the magazine.

At X, Fig. 1, in the upper part of the boiler there is the usual outlet for the hot water, and at Y in the lower part of the boiler there 65 is the return-pipe for establishing continuous circulation.

If desired, there may be arranged in the annular water-chamber about the magazine a number of hot-air tubes opening communication between the fire-box and the hood E, 70 which would give an increased heating capacity. Such tubes are shown at a' in Figs. 3 and 4; but they are not shown in Fig. 2, and they may be used or not, as may be desired.

The parts of the heater as thus described are designed to be set upon any ordinary form of base G, with suitable grate and ash-pit.

This heater is designed to burn any grade 80 of coal and is a very simple, practical, and economical heater of unusually-large heating capacity and is not liable to have its magazine burned out, as the single-shell magazines are.

Having thus described my invention, what I claim as new, and desire to secure by Letters Patent, is—

1. A hot-water heater having its boiler made in two main parts, an upper part in the form 90 of a short cylinder having draft-holes through it, and an annular and pendent water-chamber arranged inside the draft-holes and forming a fuel-magazine; a lower cylindrical boiler-section forming a water-cased fire-box, 95 a circular series of circulating-pipes establishing communication between the upper edges of the lower boiler-section, and the short cylinder of the upper section, a hood with feed-door, covering and inclosing the 100 upper boiler-section, and an outer casing extending from the upper boiler-section to the

lower boiler-section, and surrounding the circulating-pipes, substantially as and for the purpose described.

2. A hot-water heater having its boiler made in two main parts, an upper part A with vertical draft-holes *a* through it and an annular pendent water-chamber A' having vertical draft-tubes *a'* through it; and a lower part B forming a water-eased fire-box, a circular series of vertical circulating-pipes C connect-

ing the upper and lower boiler-sections, a smoke-hood E with door D, chute *d*, and smoke-pipe *e*, and an outer casing F for the circulating-pipes substantially as and for the purpose described.

MICHAEL E. HERBERT, JR.
